UNITED STATES PATENT OFFICE.

JOHN N. CLARKE, OF EVANSVILLE, INDIANA.

AWNING.

1,095,452.

Specification of Letters Patent. Patented May 5, 1914.

Application filed June 5, 1913. Serial No. 771,887.

To all whom it may concern:

Be it known that I, JOHN N. CLARKE, a citizen of the United States, residing at Evansville, county of Vanderburgh, and State of Indiana, have invented certain new and useful Improvements in Awnings, of which the following is a specification.

This invention relates to awnings.

My object is to provide in an awning of the folding laterally extending articulated or jointed arm type particularly intended for use on modern plate glass store fronts, first, a novel fixture for pivotally, swingingly and adjustably connecting the inner arm to the building; second, a novel joint or articulation connecting the inner and outer arms together; third, spring means co-operating with the outer arm adapted to automatically extend it when the awning is released or allowed to fall; fourth, a particular novel spring operating means for extending the outer arm, said spring means being anchored and housed within the inner arm; and, fifth, to generally improve the construction of jointed or articulated arm awning fixtures whereby they may be made to fold into compact arrangement across the front of the building and will, when released, automatically fall and extend themselves, subject to all necessary or desirable adjustments of inclination and position.

In the accompanying drawings I have shown and in the following description have set forth, a preferred embodiment of the invention illustrating the principle and mode of operation thereof, but such disclosure is to be considered as illustrative and not restrictive of the scope of the invention.

In the accompanying drawings:—Figure 1 is a side elevation showing the invention applied to a building; Fig. 2, an enlarged view looking toward one of the complete awning arms when folded; Fig. 3, a plan view showing the awning arms extended, the outer one being broken away and the bracket and track in section; Fig. 4, a detail perspective of the awning arms when extended; Fig. 5, a longitudinal section through the inner arm, and other parts; Fig. 6, a detail perspective of the joint member for the outer arm; Fig. 7, a section therethrough; and Fig. 8, a detail perspective of the joint member for the inner arm section.

55 The front of the building appears at 1 and

the plate glass window or store front at 2, while 3 represents the awning roll which may be constructed and mounted on the front 1 in any desired manner above the awning fixtures which constitute the present 60 invention. The awning 4 is provided with a cross bar 5 which is received in the loops 6 and pivoted at 7 to the offset ends 8 of the outer arms 9, such offsets being provided to enable the awning arms to "break" readily. 65 Suitably secured to the front 1 is a bracket fixture 10 having upper and lower arms 11 and 12 and a side arm 13. The bracket fixture is provided with a vertically disposed curved slotted part 14. Riveted or otherwise suitably pivoted at 15 to the arm 13 is a channel track 16 which is provided with a closed end 17 and a stop 18 and is provided with a nut and bolt 19, the shank of the bolt being adjustable in the slot of the part 14 by 70 which means the channel track 16 may be raised or lowered on its pivot 15 to bring it to different raised or lowered positions to thereby regulate the position of the outer arms 9 and the inner arms 20. 75

The inner arms 20 which are tubular, each have a vertically slotted head 21 through which extends a knuckle 22 and which is pivoted thereto at 23, the said knuckle having reduced ends 24 which are stepped or 80 journaled in the upper and lower arms 11 and 12. The arms 20 and 9 are thereby mounted for lateral swinging and, by virtue of the pivotal connection 23 afford a certain amount of vertical movement when folding 90 or being extended. To regulate the vertical movement and determine the exact position which the arms 9 and 20 will assume when extended, there is provided on the head 21 a roller 25 which is received in the 95 channel track 16 and bears against both walls thereof. The stops 17 and 18 determine the play of the roller, the former preventing the arms 9 and 20 when folded, and the bar 5, from striking the front 1 of the 100 building, and the stop 18 limiting the position of the said arms when extended.

The tubular arm 20 is provided with a joint member 26 having ears 27 provided with shoulders 28. The outer arm 9 is held 105 in a seat 29 on the inclined bottom 30 thereof by a pivotal connection 31. The inclination of the bottom 30 causes the arm 9 to assume an upward slant from its joint with the arm 20 outwardly so that the awning is 110

clear thereof, the arrangement being such that the arm 9 may rock up and down on the said pivotal connection 31. The seat 29 is connected by a neck 32 to a connector head 33 which is provided with keyhole slots 34 on opposite sides thereof and is located between the ears 27, a pivot 35 joining the seat 29 and connector head 33 to the ears 27, whereby the arm 9, the seat 29 and the connector head 33 can all turn in relation to the arm 20. The keyhole slots 34 are provided on opposite sides of the connector head and the shoulders 28 are provided on both of the ears 27 so that the parts may be reversed, 15 according to the conditions of installation.

Contained within the tubular arm 20 is a coil spring 36 which is connected at 37 to said arm. To the other end of the spring is connected a chain or other suitable flexible 20 connection 38 which is passed into one or the other of the keyhole slots 34 to secure it to the connector head 33. This is done while the spring is under considerable tension so that the tension of the spring normally tends 25 to hold the arm 9 extended in relation to the arm 20, but said arm 9 is disposed in laterally offset relation to the arm 20 to prevent the arms getting on a dead center and to facilitate breaking of the joint when they are 30 folded, as when the awning is rolled up.

So far as I am aware, I am the first to provide spring means of any character whatsoever for extending a laterally movable outer arm, as distinguished from any means for 35 extending the system of arms and, further, I believe myself to be the original inventor of a coil spring extending lengthwise of one of the arms and coöperating with the other arm to act on the arms at their joint for 40 the purpose of extending the outer arm in relation to the inner arm. I am aware that other means could be provided, coöperating with the joint between the arms, for extending the outer arm and I do not, therefore, 45 limit myself, except where expressed in the claims, to the particular spring means employed for this purpose.

When the awning is rolled up, as shown in Fig. 2, the sets of arms 9 and 20 of which 50 there may be two or more for any awning, are folded and lie in front of the building, above the glass store front, being there retained by any suitable means coöperating with the awning roller or with the arms 55 themselves. When released, the gravitational action of the arms 9 and 20 causes them to swing outwardly and the spring mechanism coöperating with the outer arms 9 throws them positively into extended condition, thus 60 insuring that the awning be properly taut and preventing any sagging thereof. By the provision of the spring mechanism, I obviate a defect incident to those articulated arm awnings which depend on gravity action alone and wherein the outer arms, due

to the weight of the awning fabric, often do not assume a fully extended position.

When the awning roll is wound up, the awning bracket pulling upon the bar 5, causes the arms 9 and 20 to fold underneath 70 the awning and during such folding action, the spring mechanism coöperating with the outer arms 9, keeps the awning taut and insures close winding of the awning roll.

Having thus described my invention, what 75 I claim as new and desire to secure by Letters Patent, is:—

1. An arm for awnings, consisting of inner and outer laterally movable arm sections jointed together the inner section being jointed to swing laterally, and a spring 80 extending longitudinally of and substantially parallel to said awning arm and coöperating therewith which is adapted to extend the outer arm section. 85

2. An arm for awnings, consisting of inner and outer arm sections jointed together, and a coil spring contained within and extending longitudinally of the inner arm section and having a flexible connection with 90 the outer arm section and adapted to extend said outer arm section. 95

3. In an awning arm, the combination with inner and outer arm sections, of a joint connecting them consisting of ears and a connector head received between and pivoted to said ears, and spring means coöperating with the connector head adapted to extend the outer arm section. 95

4. In an awning arm, the combination 100 with inner and outer arm sections, of a joint connecting them consisting of ears and a connector head received between and pivoted to said ears, a coil spring extending lengthwise and connected to the arm, and a flexible connection attached to said coil spring and engaged with said connector head. 105

5. An awning arm having, in combination, inner and outer arm sections, a joint 110 consisting of ears connected to one of said sections, a seat connected to the other of said sections, a connector head located between and pivoted to the ears, and a neck joining the connector head and seat, said neck being adapted for free movement in one direction and to abut one of the ears when moved in the other direction to thereby 115 determine the extended position of the outer arm. 120

6. An awning arm having, in combination, inner and outer arm sections, a joint 125 consisting of ears connected to one of said sections, a seat connected to the other of said sections, a connector head located between and pivoted to the ears, a neck joining the connector head and seat, said neck being adapted for free movement in one direction and to abut one of the ears when moved in the other direction to thereby 130 de-

termine the extended position of the outer arm, and an anchored spring coöperating with the connector head.

7. The combination with an awning arm 5 mounted to swing in a general horizontal direction, of a track disposed in general transverse relation to the arm with which said arm coöperates during its general horizontal swinging movements.

10 8. The combination with an awning fixture, of a knuckle pivoted thereto, an awning arm pivoted to the knuckle and adapted to swing therewith, and a track coöperating with the awning arm.

15 9. The combination with an awning bracket, of an adjustable track attached thereto, and an awning arm swingingly mounted on said bracket and coöperating with said track.

20 10. The combination with an awning bracket, of an upright knuckle pivoted

thereto, an awning arm pivoted to the knuckle, and a track at one end and adjustably connected at its other end to said bracket, said arm coöperating with said 25 track.

11. The combination with an awning bracket having an upright slotted part, of a channel track having an adjustable connection with said upright slotted part and pivoted to the bracket at another part, an awning arm provided with a head and having a roller coöperating with the channel track, and a knuckle passing through the head and pivoted thereto and also pivoted to the 30 bracket.

In testimony whereof, I hereunto affix my signature in presence of two witnesses.

JOHN N. CLARKE.
